CLAIM

The ornamental design for a foldable smartphone, as shown and described.

DESCRIPTION

The file of this patent contains at least one drawing/photograph executed in color. Copies of this patent with colored drawing(s)/photograph(s) will be provided by the Office upon request and payment of the necessary fee.

FIG. 1 is a front, left, top perspective view of a foldable smartphone showing a first embodiment of the new design in a fully folded condition;

FIG. 2 is a right, rear, bottom perspective view of the invention illustrated in FIG. 1;

FIG. 3 is a front view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1;

FIG. 8 is a bottom view of the invention illustrated in FIG. 1;

FIG. 9 is a front, left, top perspective view of the invention illustrated in FIG. 1 in a fully unfolded condition;

FIG. 10 is a right, rear, bottom perspective view of the invention illustrated in FIG. 1 in the condition illustrated in FIG. 9;

FIG. 11 is a front view of the invention illustrated in FIG. 1 in the condition illustrated in FIG. 9;

FIG. 12 is a rear view of the invention illustrated in FIG. 1 in the condition illustrated in FIG. 9;

FIG. 13 is a right side view of the invention illustrated in FIG. 1 in the condition illustrated in FIG. 9;

FIG. 14 is a left side view of the invention illustrated in FIG. 1 in the condition illustrated in FIG. 9;

FIG. 15 is a top view of the invention illustrated in FIG. 1 in the condition illustrated in FIG. 12;

FIG. 16 is a bottom view of the invention illustrated in FIG. 1 in the condition illustrated in FIG. 12;

FIG. 17 is a front, left, top perspective view of a foldable smartphone showing a second embodiment of the new design in a fully folded condition;

FIG. 18 is a right, rear, bottom perspective view of the invention illustrated in FIG. 17;

FIG. 19 is a front view of the invention illustrated in FIG. 17;

FIG. 20 is a rear view of the invention illustrated in FIG. 17;

FIG. 21 is a right side view of the invention illustrated in FIG. 17;

FIG. 22 is a left side view of the invention illustrated in FIG. 17;

FIG. 23 is a top view of the invention illustrated in FIG. 17;

FIG. 24 is a bottom view of the invention illustrated in FIG. 17;

FIG. 25 is a front, left, top perspective view of the invention illustrated in FIG. 17 in a fully unfolded condition;

FIG. 26 is a right, rear, bottom perspective view of the invention illustrated in FIG. 17 in the condition illustrated in FIG. 25;

FIG. 27 is a front view of the invention illustrated in FIG. 17 in the condition illustrated in FIG. 25;

FIG. 28 is a rear view of the invention illustrated in FIG. 17 in the condition illustrated in FIG. 25;

FIG. 29 is a right side view of the invention illustrated in FIG. 17 in the condition illustrated in FIG. 25;

FIG. 30 is a left side view of the invention illustrated in FIG. 17 in the condition illustrated in FIG. 25;

FIG. 31 is a top view of the invention illustrated in FIG. 17 in the condition illustrated in FIG. 25;

FIG. 32 is a bottom view of the invention illustrated in FIG. 17 in the condition illustrated in FIG. 25;

FIG. 33 is a front, left, top perspective view of a foldable smartphone showing a third embodiment of the new design in a fully folded condition;

FIG. 34 is a right, rear, bottom perspective view of the invention illustrated in FIG. 33;

FIG. 35 is a front view of the invention illustrated in FIG. 33;

FIG. 36 is a rear view of the invention illustrated in FIG. 33;

FIG. 37 is a right side view of the invention illustrated in FIG. 33;

FIG. 38 is a left side view of the invention illustrated in FIG. 33;

FIG. 39 is a top view of the invention illustrated in FIG. 33;

FIG. 40 is a bottom view of the invention illustrated in FIG. 33;

FIG. 41 is a front, left, top perspective view of the invention illustrated in FIG. 33 in a fully unfolded condition;

FIG. 42 is a right, rear, bottom perspective view of the invention illustrated in FIG. 33 in the condition illustrated in FIG. 41;

FIG. 43 is a front view of the invention illustrated in FIG. 33 in the condition illustrated in FIG. 41;

FIG. 44 is a rear view of the invention illustrated in FIG. 33 in the condition illustrated in FIG. 41;

FIG. 45 is a right side view of the invention illustrated in FIG. 33 in the condition illustrated in FIG. 41;

FIG. 46 is a left side view of the invention illustrated in FIG. 33 in the condition illustrated in FIG. 31;

FIG. 47 is a top view of the invention illustrated in FIG. 33 in the condition illustrated in FIG. 31; and,

FIG. 48 is a bottom view of the invention illustrated in FIG. 33 in the condition illustrated in FIG. 41.

The broken lines in the drawings depict portions of the foldable smartphone that form no part of the claimed design.
